(57) **CLAIM**

The ornamental design for a capsule for nail polish, as shown and described.

DESCRIPTION

FIG. 1 is a perspective view of a capsule for nail polish in a closed configuration, showing our new design;

FIG. 2 is a left side view thereof, the right side being a mirror image;

FIG. 3 is a top view thereof;

FIG. 4 is a front view thereof, the rear view being a mirror image;

FIG. 5 is a bottom view thereof;

FIG. 6 is a bottom perspective view thereof;

FIG. 7 is a perspective view in an open configuration, showing our new design;

FIG. 8 is a top view thereof;

FIG. 9 is a left side view thereof, the right side being a mirror image;

FIG. 10 is a front view thereof, the rear view being a mirror image; and,

FIG. 11 is a bottom view thereof.

Broken lines shown in the drawings are for the purpose of illustrating parts of the article that form no part of the claimed design.

1 Claim, 11 Drawing Sheets
